United States Patent Office.

FRANCIS H. WALKER, OF BOSTON, MASSACHUSETTS.

Letters Patent No. 79,418, dated June 30, 1868.

IMPROVEMENT IN BUTTON-HOLE CUTTERS.

The Schedule referred to in these Letters Patent and making part of the same.

TO ALL WHOM IT MAY CONCERN:

Be it known that I, FRANCIS H. WALKER, of Boston, in the county of Suffolk, and State of Massachusetts, have invented a new and improved Button-Hole Cutter; and I do hereby declare that the following is a full, clear, and exact description thereof, reference being had to the accompanying drawings, making a part of this specification, in which—

Figure 1 is a perspective view of the improved instrument complete.

Figure 2 is a sectional view of the jaws and anvil.

Figure 3 is a view showing the anvil in three different positions with respect to the cutter.

Similar letters of reference indicate corresponding parts in the several figures.

This invention relates to a new and useful improvement on devices which are designed for cutting button-holes of different lengths in cloth.

The object of the invention is to so construct the anvil or bed upon which the knife cuts, that it shall present surfaces of different lengths on both sides of it upon which to cut; also to so construct such anvil that it is adapted for being held in place upon one of the jaws of a pair of jointed levers, by means of a thumb-screw and a fixed centre-pin, about which latter the anvil can be adjusted when released from set-screw, as will be hereafter described.

To enable others skilled in the art to understand my invention, I will describe its construction and operation.

In the accompanying drawings, A A' represent two levers, which are constructed with jaws D D', and jointed together at C, in any suitable manner, like a pair of common pincers.

The spring B, which is between the handle portions of the levers, is intended for separating the jaws when they are not forcibly held together.

The jaw D is provided with a knife-blade, E, secured fast to it by set-screws, which knife should be as long as the longest button-hole required to be cut. This jaw is also provided with an eyelet-punch, a, which is inserted through a hole made through the jaw at the rear edge of the knife, and confined in place by a set-screw, b, shown in fig. 1. The knife and punch are fitted together in such manner that, in the act of cutting the slits with the knife, the punch will leave at one end of each slit an eye, such as is required in working button-holes. The screws which confine the knife in place may pass through oblong holes through this knife, which will allow it to be adjusted for wear in sharpening it.

Beneath the cutting-devices E and a, and applied to the jaw D', is an anvil or cutting-bed, G, upon which these devices cut.

This anvil is constructed with a number of steps, g g', upon one end, and with a recess of a circular form in its opposite end. It has also a number of screw-holes made through it, which are arranged concentrically to the axis of the semicircular recess S. The recess S, in the rear end of the anvil, or that end which comes nearest the joint of the levers A A', is adapted for receiving a button-head pin, c, which is fixed into the upper surface of the jaw D, in the middle of its width, which pin will hold the anvil down in place, and allow its front end to be moved laterally about the axis of the pin. The front end of the anvil G is confined in place, when properly adjusted, by means of a thumb-screw, h, which enters one or the other of the screw-holes which are made through the anvil. The stem of the thumb-screw h is tapped through the jaw D' from below, and passes only partly through the anvil, as shown in fig. 2.

The recess in the back end of the anvil (shown at S) is constructed with a central shoulder, shown in fig. 2, which fits beneath the head upon central pin c, whichever side of the anvil be turned up, and the screw-holes through the anvil are adapted for receiving the thumb-screw h, whichever side of the anvil be up. Thus it will be seen that the anvil is reversible, and can be used with either side up.

The distances from the centre of pin c to the stepped edges g g g, on one side of it, are greater than the distances from this pin c to the stepped edges g' g' g', on the opposite side thereof; consequently it will be seen that for the different steps of both sides of the anvil, a different length of button-hole will be made, as the knife

cannot cut the fabric beyond the edges of the steps. One side of the anvil presents surfaces upon which to cut comparatively short button-holes, and the opposite side presents surfaces upon which longer button-holes can be cut.

The different lengths of button-holes could be cut upon the anvil G by adjusting it bodily in a lateral direction beneath the knife and punch, but this adjustment would not be as simple and quickly effected as the single screw and fixed pivot-pin.

In practice, a number of the stepped anvils may accompany each instrument, each one of which anvils may give different lengths of surfaces upon which to cut, and if desirable, each one of the steps upon the ends of the anvils may be marked, so as to indicate the length of the button-hole which would be cut upon it.

Having described my invention, what I claim as new, and desire to secure by Letters Patent, is—

1. A stepped anvil or cutter-bed, G, adapted for use in conjunction with a knife, E, for cutting button-holes, substantially as described.
2. A reversible stepped anvil or cutting-bed, G, combined with retaining pivot-pin c, set-screw h, and cutter E, substantially as described.
3. A reversible stepped anvil or cutting-bed, G, substantially as and for the purpose described.

FRANCIS H. WALKER.
